Sullivan

[11] Patent Number: Des. 412,431

[45] Date of Patent: ** Aug. 3, 1999

[54] **66-110 COMBINATION BLADE FOR USE IN
MAKING ELECTRICAL CIRCUIT
CONNECTIONS**

[76] Inventor: **Robert W. Sullivan**, 3310 Los Nogales
Rd., Simi Valley, Calif. 93063

[**] Term: **14 Years**

[21] Appl. No.: **29/091,322**

[22] Filed: **Jul. 28, 1998**

[51] LOC (6) Cl. **08-05**

[52] U.S. Cl. **D8/14**

[58] **Field of Search** D13/133; D8/14;
439/392, 395, 396, 397; 29/729, 739, 764

[57] CLAIM

The design for a 66-110 combination blade for use in making electrical circuit connections, as shown.

DESCRIPTION

FIG. 1 is an isometric, top and front view of a 66-110 combination blade for use in making electrical circuit connections showing my new design;

FIG. 2 is an isometric, bottom and rear view of the combination blade;

FIG. 3 is a top view;

FIG. 4 is a bottom view;

FIG. 5 is a front view;

FIG. 6 is a right side view;

FIG. 7 is a rear view; and,

FIG. 8 is a left side view of my combination blade.
